UNITED STATES PATENT OFFICE.

FRANKLIN HARDINGE, OF CHICAGO, ILLINOIS, ASSIGNOR TO HARDINGE BROTHERS, INC., OF CHICAGO, ILLINOIS, A CORPORATION OF ILLINOIS.

OIL BURNER.

Application filed May 5, 1923. Serial No. 336,863.

My invention relates to improvements in oil burners, and is particularly concerned with the provision of an oil burner comprising a pilot light for igniting the oil spray formed by the atomizer of the burner, and means for controlling the supply of gas to said pilot light and the supply of oil to said burner.

It sometimes happens, during the operation of an oil burner, that the flame becomes extinguished, and unless means are provided for relighting the combustible mixture formed by the burner, or for shutting off the supply of fuel to the burner, considerable damage may be done. This extinction of the flame is sometimes caused by water or some other impurity in the oil passing through a small orifice, and for the time being interrupting the supply of oil to the atomizer of the burner so that for an instant the combustible mixture is discontinued, and the flame consequently becomes extinguished.

One of the objects of my invention is to provide an oil burner, and particularly an oil burner in which mechanical means are used for atomizing the oil, with a pilot light arranged to ignite the combustible mixture whenever it becomes extinguished.

Another object of my invention is to provide a pilot light, comprising a plurality of jets so arranged relatively to the walls of the fire box in which the burner is located that the current of air produced in the fire box by the burner will cause the jets of the pilot light to act as Bunsen burners, so as to insure the ignition of even the very heaviest grades of fuel oil.

Another object of my invention is to provide means for controlling the pilot light so that it will consume only a very small quantity of gas when the burner is not in operation.

Another object of my invention is to provide means for shutting off the supply of fuel to the burner whenever the burner is not in operation. This is of particular importance where the means for supplying fuel to the burner comprise a pressure tank which might continue for a short time to supply oil to the atomizer, even after the burner has ceased to operate.

A still further object of my invention is

to provide gas and oil control means of the character described, which are actuated by a common means.

Other objects of my invention will appear as this description progresses, reference being had to the accompanying drawings, in which—

Figure 1 is a partial section through a furnace and oil burner embodying my invention;

Figure 2 is a fragmentary elevation of a portion of the construction shown in Figure 1, showing certain details of construction of the means for controlling the flow of gas to the pilot light and oil to the atomizer of the burner;

Figure 3 is a sectional detail, partially in side elevation, showing further details of construction of the apparatus shown in Figures 1 and 2, and

Figure 4 is a transverse section taken on line 4—4 of Figure 2.

Throughout the several views, similar reference characters are used for referring to similar parts, and the several sections are taken looking in the directions of the small arrows.

I have illustrated my invention as being embodied in an oil burner comprising a suitable bed plate 5, upon which is removably mounted the base plate 6. At the inner end of this base plate is a suitable head 7 in which is rotatably mounted a tubular outwardly flaring atomizer 8, the upper end of which is provided with suitable fan blades or vanes 9 for supplying air to the atomized fuel discharged from the knife edge 10 of the atomizer. The atomizer projects through an opening in a ring 11 forming part of the bottom 12 of the fire box of the furnace.

The atomizer 8 is rotated by means of the motor 13, which is connected therewith through a suitable universal coupling 14, shaft 15 and connecting gearing located in the head 7.

Fuel is supplied to the atomizer by means of a pump 16 geared to the shaft 15, this pump being preferably of the gear type. The pump 16 withdraws the oil from the tank 17 through the pipe 18, and delivers it through the pipe 19 to a pressure chamber 20 from which it flows through the pipe 21 to the stand pipe 22, which projects up-

wardly through the head 7 and the hollow spindle upon which the atomizer 8 is mounted.

For controlling the rate of supply of fuel to the nozzle, I provide a pressure regulating valve 23 which is located in a pipe 24 forming a by-pass between the upper end of the pressure chamber and the return pipe 25 which leads from the lower end of the 10 pressure chamber to the supply tank 17, and which is used for periodically removing the water and sediment which collects in the lower end of the pressure tank. A valve 26 is placed in the pipe 25 to enable the 15 operator easily to drain the contents of the pressure chamber. A needle valve 27 in the pipe 21 provides means for controlling the rate of supply of oil to the atomizer.

The construction thus far described is 20 merely illustrative, and forms no part of my present invention except as the elements thereof co-operate with my invention about to be described.

The pipe 21 has a valve V inserted therein 25 comprising the body member 28 having oppositely disposed ports for communicating with the two sections of the pipe 21, and a longitudinally extending bore 29 which communicates with the bore 30 of the body 30 member. A valve 31 is slidably mounted in the bore 29, and has an annular groove 32 formed therein which may be brought into registry with the two parts of the bore 30 so as to establish communication between 35 these parts.

A bell crank lever 33 has one arm 33' thereof pivotally connected with the outer end of the valve 31 by means of a pin 34. The arm 33' is provided with a slightly 40 elongated opening 35 in which the pin 34 has a limited sliding movement to compensate for the angular movement of the bell crank lever.

The arm 33'' of the bell crank lever has a 45 roller 36 secured to its free end. This roller travels in a groove 37 formed in a collar 38, which is slidably mounted upon the shaft 15 and compelled to rotate therewith by means of the spline 39 (see Fig. 3), which 50 slides in the longitudinally extending slot 40 formed in the shaft 15.

The shaft 15 has a second collar 41 rigidly secured thereto by means of a set screw 42, or in any other suitable manner. Two 55 links 43 are pivotally mounted in slots 44 formed in opposite sides of the collar 38 by means of pivot pins 45. Another pair of links 46 are pivotally mounted in suitable slots 47 formed in opposite sides of the collar 41. Each link 46 has a bifurcated end for receiving one end of one of the links 43, and is secured thereto by means of a pivot pin 48 so as to form a flexible joint. A spring 49 60 is interposed between the two collars to 65 yieldingly oppose the movement of the collar

38 toward the collar 41. I preferably interpose an elongated sleeve 50 between the collar 38, the spring 49 and the shaft 15. The outer end of this sleeve, by abutting against the tubular projection 51 of the 70 collar 41, acts as a stop for limiting the movement of the collar 38 toward the collar 41.

From the above description, it will be apparent that when the shaft 15 is rotated, 75 the arms 43 and 46 will move outwardly to the dotted line position shown in Figure 3 so as to move the collar 38 toward the collar 41. This movement is transmitted to the bell crank lever 33 through the roller 36, 80 and causes the bell crank lever to move about its pivot point 52, thereby withdrawing the valve 31 from the bore 29 a distance sufficient to bring the annular groove 32 into registry with the two portions of the bore 85 30, and thus permitting the flow of fuel to the atomizer.

In order to insure the continued operation of the burner even though the flame is interrupted from time to time, I provide a 90 pilot light 53 which is preferably in the form of three jets located in the well 54 formed in the bottom of the fire box. The tops of these jets are located below the inner surface of the bottom of the fire box, so that the air discharged from the atomizer 8 will not extinguish the flames of these jets. It should also be noted that the well 54 is located close to the wall 55 of the fire box. I prefer to thus position the pilot light because I have discovered that in this position the flames, issuing from the pilot jets, 95 assume the characteristics of the flame of a Bunsen burner, when they are struck by the current of air from the atomizer. It is, of course, understood that such a flame is very much hotter than the ordinary gas flame so that it insures quick ignition of the combustible mixture formed by the atomizer, even though the oil used is of a comparatively heavy grade and correspondingly difficult to ignite.

To economize in the amount of gas consumed by the pilot light, I provide a valve V' which is, in all respects, similar to the valve V, except that a boss 56 is formed on one side of the body member of the valve V' and has formed therein a by-pass 57 which can be controlled by means of the adjustable needle valve 58 to regulate the size of the flames of the pilot light jets when the burner is not in operation. It will, of course, be understood that the by-pass 57 provides a passageway for the flow of a limited amount of gas around the valve V' when it is closed 105 so as to constantly maintain the pilot light 110 in action.

The valve V' is actuated by mechanism 115 similar to that which I have above described for actuating the valve V, and further de-

scription thereof appears to be unnecessary.

Whenever the collar 38 moves toward the collar 41, upon rotation of the shaft 15, it opens the valve V' as well as the valve V, and thus permits an increased quantity of gas to flow to the jets of the pilot light. This increased quantity of gas produces a much higher flame in the fire box, and when this flame is struck by the current of air 10 issuing from the atomizer, it, as stated above, assumes the character of a Bunsen burner flame and continues to burn in this manner as long as the burner is in operation. Whenever the motor stops, the spring 15 49 moves the collar 38 away from the collar 41, and thus closes both valves V and V', thereby cutting off the supply of oil to the atomizer, and limiting the supply of gas to the pilot light to the amount which flows past 20 the valve 58 in the by-pass 57.

While I have described the details of construction of the preferred embodiment of my invention, it is to be clearly understood that my invention is not limited to these details, 25 but is capable of other adaptations and

modifications within the scope of the appended claims.

Having thus described my invention, what I claim is:

1. The combination in an oil burning apparatus of a rotary atomizer, means for rotating the atomizer, means for supplying oil to the atomizer under pressure comprising a valve, a pilot light for the atomizer having a gas supply feed means with a valve 30 therein, and common means actuated by the actual rotation of the atomizer for opening and closing both said valves.

2. The combination of an oil supply pipe for oil burners; a gas supply pipe for the 40 pilot of said burners; valves in said pipes one for regulating the flow of gas and the other for regulating the flow of oil; a motor; a governor actuated thereby; and means actuated by the governor for controlling the operation of said valves.

In witness whereof, I hereunto subscribe my name this 21st day of April, 1923.

FRANKLIN HARDINGE.
